UNITED STATES PATENT OFFICE.

JOHN BOE, OF GRAVELBOURG, SASKATCHEWAN, CANADA.

MECHANICAL TOY.

1,377,054.

Specification of Letters Patent.

Patented May 3, 1921.

Application filed August 22, 1916. Serial No. 116,373.

To all whom it may concern:

Be it known that I, JOHN BOE, a subject of the King of Great Britain, residing at Gravelbourg, in the Province of Saskatchewan and Dominion of Canada, have invented certain new and useful Improvements in Mechanical Toys, of which the following is a specification.

This invention relates to improvements in mechanical toys, one object of the invention being the provision of an amusing toy that simulates a threshing machine in miniature, it having a main casing in which is mounted miniature mechanism for threshing the straw, separating the grain therefrom, and separating the straw and carrying it away from the machine.

A further object of the invention is the provision of a toy, which is simple, durable and comparatively inexpensive, it also being ornamental and attractive in appearance.

In the accompanying drawings:—

Figure 1 is a perspective view of the complete toy.

Fig. 2 is a similar view taken from the opposite side.

Fig. 3 is a vertical longitudinal sectional view through the complete toy.

Fig. 4 is a perspective view of the feeding table and blower box casing.

Figs. 5, 6, 7 and 8 are detail views of various elements of the toy.

Referring to the drawings, the numeral 10 designates the casing of the machine, which 35 is provided with the top 11, having the recessed portion 12, with the opening 13, at the end of the feeding table T, the portion 14 at the opening co-operating with the depressed portion 15, to form a receptacle for 40 the feed knives 16, the endless feeder chains 17 being mounted for movement about the table.

Intermediate of the lower portion of the casing 10 is the grain hopper 18, in which 45 is mounted the feeding screw 19, that delivers the threshed grain to the lower end of the elevator chute 20, in which is mounted the endless conveyer or elevator 21, which delivers into the directing spout 22.

50 Also journaled in the casing to receive the material is the threshing cylinder 24, the

shaft of the cylinder being extended exteriorly of the casing and connected by the belt 25, so that such belt will operate the feeder belt, the feed knives, the cylinder, and also the feed screw 19, a hand operated member 26 being provided so that a child may rotate it and operate the various parts of the toy.

A blower or fan 27 is mounted at the front of the casing near the tapered portion that leads to the straw stacker or outlet pipe 28, the same being connected by the belt 29 with the shaft of the threshing cylinder. Thus the blower shaft forms in reality a drive element for all of the various rotary parts 65 of the toy.

The concave 32 is also mounted in the casing 10, so that the present toy forms a miniature threshing machine, which may be operated by hand, or by a small electric motor, or the like, if so desired.

Also disposed within the casing to receive the straw from the concave and deliver it to the blower 27, is an endless conveyer 33, driven by the belt 34 from the shaft of the 75 threshing cylinder 24.

Mounted between the laps of the conveyer 33, is a plate 35 having the screen 36, through which the grain falls into the hopper 18.

80 What I claim, as new, is:—

A device of the kind described comprising a casing, a grain hopper depending below the casing and disposed transversely thereacross, an elevator chute disposed beside the casing and connecting at its bottom with the grain hopper, the elevator chute being open at its upper end but having a downwardly directed inclined discharge spout, a feed screw rotatably mounted in the 90 hopper and having a shaft one end of which is journaled in the elevator chute, the shaft carrying a pulley disposed adjacent the bottom of the elevator chute, a pulley rotatably mounted adjacent the top of the chute 95 and adjacent that end of the discharge spout connecting with the chute, and an endless conveyer or elevator trained over said pulleys in the manner and for the purpose specified.

100 In testimony whereof I affix my signature.

JOHN BOE,
